US0D1104269S

(12) **United States Design Patent** (10) **Patent No.:** **US D1,104,269 S**
(45) **Date of Patent:** **** Dec. 2, 2025**

(54) **VETERINARY ANESTHESIA MACHINE**

(71) Applicant: **Shenzhen Mindray Animal Medical Technology Co., Ltd.**, Guangdong (CN)

(72) Inventors: **Rongdan Zhu**, Shenzhen (CN); **Weiliang Gao**, Shenzhen (CN); **Paiyu Li**, Shenzhen (CN); **Lingbo Zeng**, Shenzhen (CN)

(73) Assignee: **Shenzhen Mindray Animal Medical Technology Co., Ltd.**, Shenzhen (CN)

(**) Term: **15 Years**

(21) Appl. No.: **29/916,197**

(22) Filed: **Nov. 9, 2023**

(30) **Foreign Application Priority Data**

(57) **CLAIM**

The ornamental design for a veterinary anesthesia machine, as shown and described.

DESCRIPTION

FIG. 1 is a front side view of a veterinary anesthesia machine showing a new design;

FIG. 2 is a rear side view of the veterinary anesthesia machine shown in FIG. 1;

FIG. 3 is a left side view of the veterinary anesthesia machine shown in FIG. 1;

FIG. 4 is a right side view of the veterinary anesthesia machine shown in FIG. 1;

FIG. 5 is a top side view of the veterinary anesthesia machine shown in FIG. 1;

FIG. 6 is a bottom side view of the veterinary anesthesia machine shown in FIG. 1; and,

FIG. 7 is a front perspective view of the veterinary anesthesia machine shown in FIG. 1.

The broken lines shown in the drawings represent portions of the veterinary anesthesia machine and form no part of the claimed design.
